SIGNAL TRANSLATING APPARATUS

James M. Kendall, Woodbury Heights, N. J., assignor to Radio Corporation of America, New York, N. Y., a corporation of Delaware

Application November 1, 1932, Serial No. 640,591

12 Claims. (Cl. 179—180)

The present invention relates to signal translating apparatus of the type employed in electrical phonograph sound recording and reproducing systems, wherein the sound record is provided in a mechanical groove or other sound track, and translated into and from undulatory electric currents corresponding to the sounds to be recorded or reproduced. Such apparatus may be of the photoelectric or of the electromagnetic type and combinations thereof. The more common forms of such apparatus, of the electromagnetic type, known as electric pickup devices, are represented in the prior art by apparatus such as that shown in Kellogg Patent 1,783,044 and Weinberger Patent 1,770,501, for example.

In electric signal translating devices of the character above referred to, a vibratory system is provided, comprising, in one well known type, an armature adapted to carry a stylus for engagement with a record groove and pivotally mounted to vibrate at one end between magnetic pole pieces in association with an electrical winding or pickup coil.

The vibratory mechanism or system, of which the armature is a part, may have one or more natural periods of vibration within the audible range at which the amplitude of vibration may be over-emphasized or under-emphasized, resulting in distortion of signals being translated by the device. Obviously this is undesirable. As indicated, for example, by the construction shown in the patents above referred to, various means have been provided in the past for correcting for such conditions of operation such as damping the armature action to effectively smooth the operating characteristic as represented by the usual frequency-voltage response curve to remove the undesired peaks or resulting dips therein caused by resonance.

In general, the prior art devices employ damping and centering means comprising blocks of resilient material engaging the armature on opposite sides and are characterized by the fact that the damping means

(1) Is interposed between and connects the armature and a fixed supporting means,

(2) Is both the damping and the centering or restoring means,

(3) Has a limited damping action, because of rigidity, and

(4) Unduly loads the armature, whereby the latter is less flexibly mounted and is less responsive in the translating action because of the connection with the fixed supporting means.

The damping action is limited because of the

material employed, usually soft rubber, and because the damping means is so mounted that it attenuates desired vibrations because of its rigidity. Furthermore, the rubber ages and must be replaced occasionally for best results in operation, and while providing damping to a certain extent, does not provide enough entirely to eliminate certain peaks in the audio frequency response characteristic of electric pickup devices for high frequency electric signal translation.

It is, therefore, a primary object of the present invention to provide an improved signal translating device for electric phonograph sound recording and reproducing systems, that shall have an improved frequency response characteristic and that shall obviate the above mentioned and certain other disadvantages of known devices.

It is a further object of the present invention to provide an improved mounting, centering and damping system for the vibratory element of a device of the above character that shall effectively attenuate undesired resonant peaks in the operating characteristic thereof, without loading the armature or vibratory system appreciably outside the frequency range of such peaks, whereby the frequency response characteristic may be improved.

In accordance with the invention, in a preferred embodiment thereof, a vibratory member or armature is separately mounted in fixed pivot bearings with a torsional restoring or centering spring extending therefrom along the pivot axis, separately connected to a fixed, spaced supporting frame. The armature member is provided with a body of damping material directly secured or connected thereto. The damping body is free to vibrate and to move with the armature since it has no other support, and at least one of its largest dimensions is parallel to the plane of vibration of the armature member, the plane of vibration being at a right angle to the pivot axis of the armature.

The shaft bearings have the separate function of providing, with the pivot shaft, a fixed, independent, pivot axis for the armature member. The fixed torsional spring, which may have a low hysteresis effect as hereinafter discussed, provides a restoring and centering force without appreciably affecting the moment of inertia of the vibratory system, since it lies in the axis of vibration. The damping means has the separate function of damping the armature, and, being free to move with the armature, may be shaped to selectively remove undesired higher frequency

peaks in the operating characteristic of the device without having any appreciable damping effect at other and lower frequency ranges. By this construction, furthermore, the use of resilient material of a non-permanent nature, such as rubber, is substantially eliminated and is employed only as a friction reducing means as a part of the shaft bearing for the armature.

It is a still further object of the present invention to provide an improved electromagnetic pickup device of the type adapted to be provided with a stylus, wherein the vibratory element or armature is more flexibly mounted, thereby to reduce record wear and to improve the frequency response characteristic.

Contrasted with the selective frequency responsive damping means above mentioned, the torsional centering spring arrangement provides for restoring the vibratory element to a central normal position with a stiffness that is constant within the audio frequency band. No resonance and a very low moment of inertia are the characteristic of a restoring means of this character, and by properly choosing the material, very low mechanical hysteresis is obtained.

Hysteresis in vibratory systems is the equivalent of friction, so that when the vibratory element or armature is deflected from its normal position, it does not return exactly thereto, but only to a point where the centering force is balanced to a force that is necessary to overcome the friction. The greater the hysteresis the more off center will the armature be after it is deflected.

In electric signal translating devices of the present electric pickup type, the armature, in its unexcited condition, stands normally in a central position with one end midway between the two pole pieces. As is well known with devices of this character, in operation, the armature is deflected from the central position either by mechanical forces or by forces derived from electric currents flowing in the coil.

If rubber damping blocks are employed in connection with the armature element for restoring the armature to and for normally maintaining it in a centered position, it has been found that the hysteresis effect above mentioned is relatively high. Accordingly, to overcome the effects of hysteresis in such a case, it has heretofore been necessary to provide a restoring force in the form of a spring in certain cases, or to rely on the rubber only, the spring being thereby stiffened to overcome the hysteresis effects.

In a translating device embodying the present invention, the damping means is carried entirely by the moving or vibratory armature whereby it imparts no fixed rigidity thereto and, accordingly, the restoring force or spring may be reduced to a point which makes it possible to provide a flexible armature element or stylus carrying member and thereby appreciably to reduce record wear. In this position, the response characteristic of the device is improved because of the flexibility of the moving parts.

The invention will, however, be better understood from the following description when taken in connection with the accompanying drawing, and its scope will be pointed out in the appended claims.

In the drawing, Fig. 1 is a front view, on a greatly enlarged scale, of an electrical signal translating or pickup device embodying the invention:

Fig. 2 is a cross sectional view taken on line

2-2 of the device shown in Fig. 1, on the same scale and with a cover plate in place;

Fig. 3 is a view in perspective and partly in section, of a portion of the device shown in Figs. 1 and 2, on a still further enlarged scale;

Figs. 4 and 5 are views in perspective of details of the devices of Figs. 1, 2, and 3, showing modifications; and

Fig. 6 is a curve diagram illustrating an operating characteristic of the device shown in Figs. 1, 10 2, and 3.

Referring to Figs. 1, 2, and 3 of the drawing, 6 is the molded insulation base of an electromagnetic pickup device on which is mounted a metallic frame 7 providing magnetic pole pieces 8 to which 15 is connected a permanent magnet 9 for supplying flux thereto. An armature or vibratory member 10 provided with an integral pivot shaft 11 is journalled in the frame 7 in suitable spaced 20 bearings provided by rubber sleeves 12-12 mounted on the shaft and clamped with it between two frame members 13.

In the present example, the armature is hollow at one end and may be provided with a suitable stylus 14, which is clamped within the hollow 25 end of the armature by a clamping screw or thumb screw 15, threaded axially into the shaft 11.

The opposite end 16 of the armature is adapted to lie between the pole pieces 8 and is surrounded by a suitable electric pickup winding or coil 17 30 provided with terminal leads 18 which, in turn, are connected to output terminal members 19 embedded in the body 6 of the pickup device for external connection with an electrical circuit 35 (not shown).

The permanent magnet 9 is held in place on the frame 7 by a spring retaining member 20 connected with the body 6 in a position to engage the top of the magnet. The pickup device is also provided with an external main cover 21, 40 all as shown more clearly in Fig. 2.

It will be noted that the vibratory member or armature is pivotally mounted in the bearing sleeves 12-12 which, as hereinbefore stated, are preferably of rubber, whereby friction is avoided 45 or reduced to a minimum. The bearings are spaced, and it will be noted that the armature member is thereby prevented from movement in the radial directions. This arrangement prevents the weight of the device on the stylus from 50 displacing the armature member. In other words, the armature member is journalled in means which function exclusively as pivot bearings, to constrain the armature to rotary motion without radial movement.

The armature member is retained in a central or normal position with respect to the pole pieces 8, by an elongated spring member or torsional restoring and centering spring 22 which lies in axial extension of the pivot shaft 11 at 60 one end thereof and which is connected with said end and with a spaced bracket member 23 forming part of the frame 7. The spring may be either round or rectangular in cross section. In the present example, the spring is substantially rectangular in cross section and is flat at its ends whereby it may be secured in holes or slots in the shaft end and in the frame extension or bracket member 23.

The bracket member 23 and the spring are 70 preferably united permanently by suitable means such as by soldering (not shown), whereby the spring is rigidly connected with the frame and is rigid against movement in any direction except torsionally, that is, about its own axis 75

and that of the shaft 11. The spring is secured to the armature by any suitable means, such as by slot 24, in one end of the shaft 11, over which is forced a sleeve 25.

By this arrangement, it will be seen that the vibratory member or armature is not only rigidly constrained to rotary motion by spaced bearing means provided in a rigid frame, but it is also connected with said frame by further means comprising a torsional spring which serves to prevent longitudinal movement of the shaft and armature within the bearings should there be any tendency for such movement, and which also holds the armature resiliently centered between the pole pieces. The torsional spring connection between the armature and the frame is of such cross section, although relatively small since it is preferably of steel, that it may impart sufficient centering action to properly return the armature to and normally hold it in the centered position.

It will also be noted that the frame and the adjacent shaft end are relatively widely spaced, whereby the torsional spring may be relatively long, thereby reducing the stresses in the spring material. The stiffness of the spring is substantially constant and it is non-aging as compared with rubber as a restoring means for the armature. Being of steel and of fixed dimensions it may be made very uniform in quantity production. Furthermore, it is rigid in all directions, except torsionally, and has no resonance in itself. Because it lies in the axis of the armature pivot shaft, it has substantially no appreciable inertia or resonance in itself and has no appreciable mechanical hysteresis.

The sleeve 25 is arranged to extend in the direction of the spring 22 into the space between the frame member 23 and the main portion of the frame, and is there enlarged to form the cylinder 26 on which is mounted a block of damping material 27. In the present example, the block of damping material is rectangular in shape and is relatively thin, having at least one of its largest dimensions in a plane parallel to that of vibrational movement of the armature, that is, at a right angle to the shaft axis. The exact dimensions of the block 27 are not critical. It is desirable, however, that the moment of inertia thereof, about the axis of vibration of the armature member, shall be greater than the moment of inertia of the armature member about the same axis.

The function of the sleeve or cylinder is to provide a rigid connection between the block of damping material 27 and the armature, thereby to impart to the mass of damping material, through the cylinder, and in the plane of one of its larger dimensions, a predetermined vibratory force corresponding to that to which the armature member is subjected at its resonance peaks. The damping block is subjected to rotational and torsional movement in the example shown, but it may be attached to the armature by other means, as indicated in Fig. 4 for example, to which attention is now directed.

In Fig. 4, the armature member 10 is provided with a cylindrical extension piece 10a on which is mounted a relatively large block of damping material 27a. The damping action is similar to that provided by the block 27 in Fig. 3 and the material and the damping action per se will be further considered hereinafter; Fig. 4 being illustrative, along with the preceding figures, of an arrangement of the damping means in connec-

tion with the armature element which has been found to be satisfactory, although the arrangement shown in Figs. 1, 2, and 3 is the present preferred arrangement.

In either embodiment, the block of damping material is rigidly connected to the supporting means, such as the extension pin 10a of Fig. 4, or the cylinder 26 of Figs. 2 and 3. In general, friction may be depended upon for this connection, or in the case of a fusible material, friction, supplemented by fusion, produced by suitably heating the cylinder 26, for example by a soldering iron or the like, until the material of the block fuses and thereby more firmly adheres to the cylinder 26. In the case of non-fusing materials, these parts may be cemented together to supplement the frictional connection.

In certain cases, however, it will be desirable to provide additional means, as shown in Fig. 5, for example, for insuring that the block does not slip or twist on its supporting medium and to this end a cylinder 29, corresponding to cylinder 26 of Fig. 3, may be provided with radially extending fins 30, which will cut into and, therefore, grip the damping material when the damping block is pressed onto the cylinder.

The damping material found most suitable for the use shown, is a soft, pliable and solid substance, such as that known commercially as Glyptal, or another commercial product known as Du Pont Viscoloid, X7775-3.

The material should preferably have all the properties of a solid, but should be inert and almost fluid, while being self supporting or adapted to hold a permanent shape.

Specifically, the damping material preferably has the following properties and characteristics:

Mass.—The important thing about mass is that it has inertia, or resistance to change of velocity. The materials at present found most satisfactory have a density of about 1, but this value does not appear to be critical.

Rigidity.—One of the differences between a solid and a liquid. The material should have sufficient rigidity and mechanical strength to make it self supporting. Too much rigidity adversely affects the performance in a translating device.

Damping.—Ordinarily, most easily thought of as a property of heavy oil. The resisting force is proportional to the velocity. (In a mechanical system it is similar in its effect to resistance in an electric circuit). In regard to solids, it is often confused with hysteresis, but it relates to hysteresis as eddy currents do to magnetic hysteresis in iron. The material found most satisfactory for damping in accordance with the invention is that in which, when slightly deformed, the resisting force is nearly all due to the damping, and hardly at all to the rigidity.

Rubber fails to meet the last two of the above requirements and, therefore, as a damping medium is entirely insufficient. The present preferred materials named, however, have proved to be highly satisfactory and are, at present, preferred as damping materials for use in a system embodying the invention.

The operation of the vibratory system embodying the invention is as follows:

The damping mass or block is free to rotate with the armature when the armature is slowly deflected in a normal manner. If, however, the armature is suddenly deflected, or shock excited, as in normal operation, the outer edge portions of the mass or block will tend to stand still at first.

and then begin to rotate rather slowly until they have rotated through an angle corresponding to the angle through which the armature was suddenly deflected. The inner portion of the mass or block adjacent to the cylinder obviously must 5 rotate with the armature since it is directly connected thereto. The motion of the outer edge lags behind the motion of the inner or center portion under these conditions, and thus the material is worked or deformed, when the deflection is 10 sufficiently sudden. This deformation of the damping material causing the absorption of energy is utilized for controlling the oscillations in the vibratory system set up by the shock excitation.

15 The above described operation of the damping means is in terms of transient effects. It may be described also in terms of steady static effects. The mass reactance of the damping means is low 20 at low frequencies, and hence but little force is required to oscillate the damping block or mass. The damping and rigidity of the material are sufficient to transmit this force from the cylinder to the outside edge of the block or mass without 25 deforming the material. Hence, the entire block or mass oscillates in phase with the armature in a low frequency range.

At a higher frequency range, the damping and rigidity of the material are not sufficient to transmit 30 to the edge of the block the increased force necessary to overcome the increased mass reactance at the higher frequency and when the material is deformed, the portion near the cylinder or sleeve vibrates therewith, while the edge portions 35 tend to stand still, thereby causing the damping and rigidity of the material to become effective and to control resonance effects in the higher frequency range.

It should be noted that the damping is effective 40 only above a certain frequency. This frequency is determined by the mass, rigidity, damping, and dimensions of the material, and is so adjusted to be just below the resonance usually occurring in the 45 vibrating system, for example, in the neighborhood of 3000 cycles. This resonance is ordinarily responsible for a considerable loss of quality of reproduction, and should be eliminated if possible. By making the damping and rigidity of the 50 damping means effective at a somewhat lower frequency, this resonance may be largely suppressed, thus improving the quality of reproduction.

The advantages inherent in the free selective damping system thus provided may further be seen after a brief consideration of a system 55 wherein the damping material is bound or rigidly held, as in certain prior art devices. If, in accordance with such systems, the damping block were held by its outer edges, while the cylinder oscillates, the clamping material is worked at all 60 frequencies. This has the objection of introducing the damping and rigidity at frequency ranges wherein it is not required, thereby putting an unnecessary load on the needle point, with a consequent increase in record and needle wear. This is especially true since the major portions of recorded 65 sounds appear in a lower rather than a higher frequency range. If the load on the needle is light, or in other words, if the mechanical impedance is low, in this lower range, as is the case 70 with a construction like that of the present embodiment of the invention, a major portion of what is usually considered normal record wear is avoided. The preferred arrangement is, therefore, to have the outer peripheral portion or edges

of the damping block or mass free and the shape and mass so adjusted as to make the damping effective at a frequency somewhat below the usual resonance.

The preferred embodiment, therefore, includes 5 a torsional type damper which replaces the customary damping blocks on the tail of the armature.

If loading of the armature is unobjectionable, in 10 certain cases it may be desirable to increase the moment of inertia of the damping block as by adding to the mass at the edges by the same or heavier material, or by other suitable means such as clamping the edge of the block by a screw 15, for example.

The effect of the damping introduced is to 20 control the armature resonance. The effect of the rigidity inherent in the damping material on the operation is to extend the frequency range. The upper limit of this range depends primarily on the 25 moment of inertia of the armature and the stiffness of the stylus or needle. In general, the greater the stylus stiffness and the smaller the moment of inertia of the armature, the greater the range. To a lesser degree, it is also true that the greater 30 the centering stiffness, the greater the range. The rigidity inherent in the damping material at high frequencies is added to the centering stiffness, thereby increasing the range. Furthermore, in designing the pickup, the diameter of the cylinder and the thickness of the damper block are 35 adjusted to give the best frequency response. In the light of the electric analogy, this adjustment corresponds to impedance matching.

The torsional damper has the advantage of 40 adding the least mass to the armature, because the cylinder is located coaxially with center of oscillation of the armature. This makes its moment of inertia minimum and makes possible a design with better performance.

It has been found that the construction in accordance with the present invention, as shown and described, has an improved range of operation extending effectively to 4500 cycles as compared with previous performance of known devices of 3500 cycles.

45 From the foregoing description, it will be seen that a signal translating device in accordance with the invention comprises a vibratory element through the movement of which the translating action is effected and on which is mounted, or with which is rigidly connected, a block of material especially chosen for damping characteristics, the shape of which and the mounting means for which is determined by the frequency range 50 within which damping is desired.

It will also be seen that, in response to low 55 frequency vibrations, the damping block vibrates with the armature member as a unit, while in response to high frequency vibrations, the mass of the outer edges of the damping block have sufficient inertia to hold them substantially stationary, while the inner portion adjacent to the hub or cylinder vibrates relatively thereto permitting the absorption of the excess energy in the frequency range to which the vibratory system is responsive.

60 Thus, it will be seen that the damping means, instead of acting throughout the full audio frequency range, is selectively responsive and may 65 properly be termed "a selective damping means".

Referring now to Fig. 6, the electrical voltage-output frequency characteristic of the pickup device shown in Figs. 1, 2 and 3 is plotted in two curves 70 and 75. These curves are not plotted 75

throughout the lower frequency range, but only for the higher frequency range in which correction for distortion is desired in the particular type of translating device referred to.

5 The curve 31 indicates the operating characteristic without employing the damping block 27, and it will be noted that this characteristic indicates distortion in the region of 3500 cycles, while curve 32, showing the operation when provided with the damping block 27, is free from any appreciable peaks of that character. This indicates an improved or extended higher frequency range, or an improved performance, and shows that the resonance characteristic of the 10 vibratory system is compensated for. By varying the size and the shape of the block, the damping characteristic may, of course, be varied and may be caused to provide any degree of correction between the curves indicated for the particular example herein given. For example, if the armature is loaded, as by increasing the inertia of the edges of the damping block by means such as that hereinbefore mentioned, while the mechanical impedance is increased, 15 the frequency characteristic is not appreciably affected, as indicated by the curve 33 taken with the armature so loaded.

It should be understood, however, that the invention is not limited to electromagnetic pickup 20 devices, although the vibratory system of the present example represents the present preferred embodiment of the invention and is particularly adapted for such devices. The invention may be embodied in any signal translating 25 device having a vibratory element or system normally subject to one or more resonant peaks in the audio frequency range.

I claim as my invention:

1. In an electric signal translating device, the 30 combination with a vibratory armature member having a pivotally mounted shaft of a frequency responsive selective damping means therefor including a free mass of damping material rigidly connected with said armature shaft, and having its major portion to one side of the axis of vibration 35 of said shaft to provide a center of mass eccentric with respect to said axis and a higher moment of inertia than the armature member about the axis of vibration of said shaft.

2. In an electric signal translating device, the 40 combination with a vibratory armature member of a frequency responsive selective damping means therefor including a free mass of damping material rigidly connected with said armature member, and having its major portion to one side of the axis of vibration of said member to provide a center of mass eccentric with respect to said axis and a higher moment of inertia than the armature member about the axis of vibration 45 of said member, a supporting frame, a torsionally flexible spring bar extending axially of and from the armature to the frame and providing therewith a rigid connection for the armature.

3. In an electric translating device, the 50 combination with a vibratory armature member of a frequency responsive selective damping means therefor including a normally free mass of damping material rigidly connected with said armature member and having its major portion 55 extending to one side of the axis of vibration thereof, and means associated with said major portion for variably applying a load to said mass of damping material at will.

4. In an electric signal translating device, the 60 combination with a vibratory armature member,

of a block of damping material having a direct connection only with and surrounding an extension of the armature member to move therewith as a unit in response to vibrations within a predetermined frequency range, said damping material having the characteristic of offering to an external force tending to distort it a resisting force which is proportional to the velocity of distortion whereby it moves only in part adjacent to and in a region surrounding said extension of the armature member freely in response to vibrations within a second frequency range.

5. In an electric pickup device, the combination of a supporting frame, an armature member journaled in said frame to vibrate about a fixed pivot axis, an elongated torsional spring member having substantially no moment of inertia about said axis connected with the shaft and extending axially therefrom into rigid connection with a portion of the frame, and a block 10 of vibration damping material rigidly connected with the armature member to vibrate therewith about said pivot axis.

6. In an electric pickup device, the combination of a supporting frame, an armature member journaled in said frame to vibrate about a fixed pivot axis, an elongated torsional spring member connected with the shaft and extending axially therefrom into rigid connection with a portion 15 of the frame, a block of vibration damping material rigidly connected with the armature member to vibrate therewith about said pivot axis, and a cylinder surrounding said torsional spring member and providing said connection between the armature and the block of damping material.

7. In an electric pickup device, the combination of a supporting frame, an armature member journaled in said frame to vibrate about a fixed pivot axis, an elongated torsional spring member having substantially no moment of inertia 20 about said axis connected with the shaft and extending axially therefrom into rigid connection with a portion of the frame, and a block of vibration damping material rigidly connected with the armature member to vibrate therewith about said pivot axis, the block of damping material having at least one of its greater dimensions in the plane 25 of vibration in which it moves, and having a mass such that it has a higher moment of inertia about said pivot axis than the armature.

8. In an electric pickup device, the combination of a supporting frame, an armature member journaled in said frame to vibrate about a fixed pivot axis, an elongated torsional spring member having substantially no moment of inertia 30 about said axis connected with the shaft and extending axially therefrom into rigid connection with a portion of the frame, and a block of vibration damping material rigidly connected with the armature member to vibrate therewith about said pivot axis, the block of damping material having at least one of its greater dimensions in the plane of vibration in which it moves, and said block being freely movable as a unit 35 with the armature member within a predetermined low frequency range and having a mass such that it has a higher moment of inertia about said pivot axis than said armature member.

9. In an electric signal translating device, the 40 combination with a vibratory armature member, of means providing a fixed pivot axis for the armature member, a torsional spring member connected at one end with said armature member and extending therefrom along said pivot axis, a

fixed supporting means for the armature member rigidly connected with the opposite end of said spring member, said spring member having a lower moment of inertia than the armature member about said pivot axis, and a block of damping material connected with the armature to move therewith as a unitary mass about said pivot axis, said block being of such shape and having a mass such that it has a higher moment of inertia 10 about said pivot axis than the armature member.

10. An electric pickup device including, in combination, a pivotally mounted armature member, torsional spring means therefor coaxial therewith at one end and independent of the pivotal 15 mounting, said spring means having substantially no moment of inertia about the armature pivot axis, and damping means for said armature member having a common axis of rotation therewith, said damping means including a body of 20 damping material connected with said armature and having its major portion extending to one side of said axis whereby said damping means has a moment of inertia about said axis greater than that of the armature.

25 11. An electric pickup device including in com-

bination, a pivotally mounted armature member, torsional damping means for the armature and centering means for the armature member, said centering means extending axially along the pivot axis of the armature and having substantially no moment of inertia with respect thereto and said damping means surrounding said axis and comprising a block of damping material having a major dimension extending at a right angle to the said axis of rotation.

12. In an electric signal translating device, the combination of an armature member having a pivot shaft, a frame in which said pivot shaft is journaled, a cylindrical extension piece for the armature member, a block of damping material mounted on and surrounding said extension piece, said block of damping material having dimensions and shape such that its outer edges are relatively widely spaced from said cylindrical extension piece, an elongated torsional spring 20 member connected with the shaft and extending axially therefrom into rigid connection with a portion of said frame.

JAMES M. KENDALL.
